DECORATIVE TOY FOR CHRISTMAS TREES

Harry J. Brown and Regis G. Bailey, Pittsburgh, Pa.
Application November 15, 1954, Serial No. 468,858

3 Claims. (Cl. 46—240)

This invention relates to the class of toys, and more particularly to a novel decoration for use in association with Christmas trees or the like.

The primary object of the present invention resides in the provision of a highly attractive and amusing base for a Christmas tree or like ornament on which toy vehicles will move in opposite directions along substantially circular trackways without any propulsion means being visible.

The construction of this invention features means for mounting channel-shaped bands for rotation in opposite directions, the bands supporting magnets which attract other magnets carried by the wheeled vehicles riding in trackways of an upper base portion positioned above the bands.

Still another object of the invention resides in the provision of means for rotating magnet carrying bands in opposite directions using a common friction drive wheel.

Still further objects and features of this invention reside in the provision of a toy that is simple in construction, highly efficient in operation, especially attractive in appearance, and capable of providing considerable amusement.

These, together with the various ancillary objects and features of the invention which will become apparent as the following description proceeds, are attained by this toy, a preferred embodiment of which has been illustrated in the accompanying drawings, by way of example only, wherein:

Figure 1 is a plan view of the toy with the Christmas tree or like ornament with which the toy is associated being shown in section;

Figure 2 is a vertical sectional view of the toy comprising the present invention and illustrating the manner in which the toy may be associated with the stand of a Christmas tree and with the Christmas tree itself;

Figure 3 is a plan view of one of the lower base sections;

Figure 4 is a partial perspective view in an exploded state of a sectional band;

Figure 5 is a partial plan view illustrating the construction of the drive means for actuating the bands; and

Figure 6 is a sectional detail view illustrating the construction of the drive means for the bands in detail.

With continuing reference to the accompanying drawings wherein like reference numerals designate similar parts throughout the various views, reference numeral 10 designates the trunk of a Christmas tree or like ornament with which the toy generally designated by reference numeral 12 is adapted to be associated. This toy 12 includes a lower base portion 14 which is recessed, as at 16, for reception and support of an upper base portion 18. The lower base portion 14 and the upper base portion 18 can be constructed from any suitable material, such as plaster of Paris, papier-mache or the like.

Bonded to the inner edge, as at 20, of the upper base portion 18, is a piece of fabric cloth 22 provided with drawstrings, as at 24, which is adapted to be tied about

2

the trunk of a tree. The cloth 22 may be painted and configurated to depict a hilly terrain, while the lower base portion 14 and upper base portion 18 may have any desired configurations. The upper base portion 18 is provided with a pair of trackways 26 and 28 which are concentric with respect to each other.

The lower base portion 14 and the upper base portion 18 are formed in sections so that they may be readily positioned about the base of the tree 10 and may be held together by any suitable fasteners, such as those indicated at 30, see Figure 3.

Mounted within the lower base portion 14 is a motor 32 supplied by electrical current through a conductor 34 which is connected to a variable transformer 36 or the like for controlling flow of current to the motor 32.

The motor 32 drives a shaft on which a friction wheel 38 is mounted, the friction wheel being adapted to engage metallic bands 40 and 42. The metallic bands, see Figure 4, are arranged in sections, as at 44 and 46, with the section 44 being provided with an aperture 48 in one end thereof and the section 46 having a connecting connector 50 adapted to be engaged within the aperture 48 to hold the sections 44 and 46 together. Likewise, the other ends of the semi-circular sections 44 and 46 are provided with suitable means for attachment.

Carried on shafts 52 and 54 journaled in the lower base portion 14 and offset by means of eccentric arms 56 and 58 are a pair of rollers 60 and 62 which are normally urged together by a spring 64 terminally attached to the arms 56 and 58. The roller 60 is provided with an upper flange 66 and a lower flange 68, while the roller 62 is provided with an upper flange 70 and a lower flange 72. The rollers 60 and 62 are adapted to resiliently hold the bands 40 and 42 in engagement with the roller 38, the channel-shaped bands 40 and 42 being received between the upper and lower flanges 66, 68, and 70, 72.

Spaced idler wheels which are indicated at 74 are engaged by the channel-shaped bands 40 and 42 which are held against the idler wheel 74 by means of spring pressed rollers 76 and 78. The wheels 74 and the rollers 76 and 78 are positioned as may be necessary in annular spaced relationship along the lower base portion 14.

Carried by the channel-shaped bands 40 and 42 and magnetically attracted thereby are magnets, as at 80 and 82. The magnets 80 and 82 cooperate with other magnets 84 and 86 positioned in miniature wheeled vehicles 88 and 90. The vehicles 88 and 90 are positioned on the trackways 26 and 28 in the upper base portion 18.

The operation of this toy is quite simple. With the motor 32 revolving the friction drive wheel 38, the rollers 60 and 62 will hold the bands 40 and 42 in engagement with the friction drive wheel 38 which therefore rotates the bands 40 and 42 in opposite directions. The magnets 80 and 82 while they remain seated in the bands 40 and 42 will attract the magnets 84 and 86, and hence, while the bands 40 and 42 are rotating, and with the upper base section 18 remaining stationary, the vehicles 88 and 90 will follow the magnets 80 and 82. Thus, with no apparent means of locomotion, vehicles will be seen traveling along the trackways 26 and 28 in a novel and highly entertaining manner.

From the foregoing, the construction and operation of the device will be readily apparent and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A toy comprising a lower base portion having a mo-

for driving a friction drive wheel mounted thereon, other wheels rotatably mounted on said lower base portion, pairs of spring pressed rollers mounted on said lower base portion and resiliently urged inwardly towards said drive wheel and said other wheels, annular metallic bands received between said rollers and said drive wheel and said other wheels, magnets carried by said bands, an upper base portion overlying said bands, said upper base portion having trackways in alignment with said bands, said lower base portion and said upper base portion being sectional and encompassing the base of an ornament, and a flexible cloth secured to said upper base portion engaging said ornament.

2. A toy comprising a lower base portion having a motor driving a friction drive wheel mounted thereon, other wheels rotatably mounted on said lower base portion, pairs of spring pressed rollers mounted on said lower base portion and resiliently urged inwardly towards said drive wheel and said other wheels, annular metallic bands received between said rollers and said drive wheel and said other wheels, magnets carried by said bands, and upper base portion overlying said bands, said upper base portion having trackways in alignment with said bands, said rollers each having upper and lower flanges for guidingly receiving said bands therebetween, said bands being sectional and being of channel shape, and wheeled vehicles having magnets carried thereby positioned on said trackways, said lower base portion and said upper base por-

tion being sectional and encompassing the base of an ornament, and a flexible cloth secured to said upper base portion engaging said ornament.

3. A toy comprising a lower base portion having a motor driving a friction drive wheel mounted thereon, other wheels rotatably mounted on said lower base portion, pairs of spring pressed rollers mounted on said lower base portion and resiliently urged inwardly towards said drive wheel and said other wheels, annular metallic bands received between said rollers and said drive wheel and said other wheels, magnets carried by said bands, an upper base portion overlying said bands, said lower base portion and said upper base portion being sectional and encompassing the base of an ornament, and a flexible cloth secured to said upper base portion engaging said ornament, said upper base portion having trackways in alignment with said bands, and wheeled vehicles having magnets carried thereby positioned on said trackways.
